(57) **CLAIM**

The ornamental design for holder for electric toothbrushes and the like, as shown and described.

DESCRIPTION

FIG. 1 is a perspective view of the holder;
FIG. 2 is a top plan view of the holder of FIG. 1;
FIG. 3 is a front view of the holder of FIG. 1 with the back view being the mirror image;
FIG. 4 is a right side view of the holder of FIG. 1 with the left side being the mirror image;
FIG. 5 is a bottom plan view of the holder of FIG. 1;
FIG. 6 is a perspective view of an alternative embodiment of the holder;
FIG. 7 is a top plan view of the holder of FIG. 6;
FIG. 8 is a front view of the holder of FIG. 6 with the back view being the mirror image;
FIG. 9 is a right side view of the holder of FIG. 6 with the left side being the mirror image;
FIG. 10 is a bottom plan view of the holder of FIG. 6;
FIG. 11 is a perspective view of a second alternative embodiment of the holder;
FIG. 12 is a top plan view of the holder of FIG. 11;
FIG. 13 is a front view of the holder of FIG. 11 with the back view being the mirror image;
FIG. 14 is a right side view of the holder of FIG. 10 with the left side being the mirror image;
FIG. 15 is a bottom plan view of the holder of FIG. 10;
FIG. 16 is a perspective view of a third alternative embodiment of the holder;
FIG. 17 is a top plan view of the holder of FIG. 16;
FIG. 18 is a front view of the holder of FIG. 16 with the back view being the mirror image;
FIG. 19 is a right side view of the holder of FIG. 16 with the left side being the mirror image; and,
FIG. 20 is a bottom plan view of the holder of FIG. 16.
